US0D1020410S

(12) **United States Design Patent** (10) Patent No.: **US D1,020,410 S**
(45) Date of Patent: ** Apr. 2, 2024

(54) **CUP HOLDER**

(71) Applicant: **Shenzhen Zhengling Technology Co., Ltd.**, Shenzhen (CN)

(72) Inventors: **Xiaofei Qiu**, Shenzhen (CN); **Zhicheng Xie**, Shenzhen (CN)

(73) Assignee: **SHENZHEN ZHENGLING TECHNOLOGY CO., LTD.**, Shenzhen (CN)

(**) Term: **15 Years**

(21) Appl. No.: **29/816,908**

(22) Filed: **Nov. 26, 2021**

(51) LOC (14) Cl. **09-05**

(52) U.S. Cl.

USPC **D7/620**; D7/701; D7/624.2

(58) Field of Classification Search

USPC D7/550.1, 552.1, 553.1, 553.2-55, 554.1, D7/554.3, 701-708; D12/419

(57) **CLAIM**

The ornamental design for a cup holder, as shown and described.

DESCRIPTION

FIG. 1 is a perspective view of a cup holder showing our new design;

FIG. 2 is another perspective view thereof;

FIG. 3 is another perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a cross-sectional view taken along the line 10-10 shown in FIG. 8;

FIG. 11 is an enlarged view of portion 11 shown in FIG. 2; and,

FIG. 12 is an enlarged view of portion 12 shown in FIG. 3. The dash-dash broken lines in the drawings depict portions of the cup holder that form no part of the claimed design. The dot-dash broken lines represent boundaries of the enlarged portions and form no part of the claimed design.

1 Claim, 12 Drawing Sheets
